UNITED STATES PATENT OFFICE.

THOMAS C. SISK, OF OAKLAND, CALIFORNIA.

RAILWAY-SPIKE.

Specification of Letters Patent. Patented July 9, 1912.

1,031,878.

Application filed July 11, 1911. Serial No. 637,922.

To all whom it may concern:

Be it known that I, THOMAS C. SISK, citizen of the United States, residing at Oakland, in the county of Alameda and State of California, have invented new and useful Improvements in Railway-Spikes, of which the following is a specification.

This invention relates to railway fastening devices, and especially to spikes.

10. The object of the present invention is to provide a simple, inexpensive, substantial spike of peculiar and special design, having particularly the object of insuring the spike against accidental movement or withdrawal.
15. The invention consists of the parts and the construction and combination of parts, as hereinafter more fully described and claimed, having reference to the accompanying drawings, in which—
20. Figure 1 is a central, vertical section through the spike. Fig. 2 is an edge view of the spike. Fig. 3 is a view showing the spike in its position when driven into a tie.

The present invention comprehends a railway spike, as 2, having a head portion 3 which projects at one part considerably beyond the side of the spike so as to have a large area to rest upon the surface of the rail to be secured.

25. The shank 4 of the spike may be of suitable proportions and dimensions, and is shown as centrally slotted so as to form two separable, flexible prongs 5, having their lower ends beveled from the inside outwardly, as at 6, so as to form sharp points, which, when the spike is driven into the wood or tie, serve to deflect the prongs 5 outwardly into the position shown in Fig. 3, which illustrates the spike when driven
30. home.

One of the particular and salient features of the present invention, in addition to the

separable, flexible prongs, is the provision of a wedge-like surface or lip 7 which is formed about one-third of the way, more or less, down the shank 4 beneath the head 3 of the spike. This lip 7 is formed on the side or surface of the spike beneath the longer overlapping portion of the spike head 3. The rearward, upward curvature of the surface 8 away from the lip 7 is of such degree that when the spike 2 is driven home into a tie, the spike is bodily advanced or jammed against the rail to be secured by reason of the wedge-like operation of the surface 8 adjacent to the cutting lip 7 against the contiguous wood.

The combined effects of the separable, flexible spike prongs 5, which spread after the spike has been driven into the tie, in addition to the locking or jamming action due to the provision of the wedge surface 8, is that the spike takes an extremely tenacious hold in the wood of the tie and is not easily dislodged by the expansion or shrinkage of the tie or by stresses resulting from actions on the rail, which is indicated at 10.

Having thus described my invention, what I claim and desire to secure by Letters Patent is—

A railway spike having a head with a portion projecting considerably to one side of the body of the spike and having a shank bifurcated to form separable prongs, and a wedge-like portion formed between the prongs tapering upwardly and rearwardly from one side of the shank.

In testimony whereof I have hereunto set my hand in the presence of two subscribing witnesses.

THOMAS C. SISK.
